CLAIM

The ornamental design for a decorative buckle for a light string, as shown and described.

DESCRIPTION

FIG. 1 is a front, right, and top exploded perspective view of a decorative buckle for a light string showing my new design, the decorative buckle comprises a cover and a receiver;
FIG. 2 is a second exploded view thereof;
FIG. 3 is a third exploded view thereof;
FIG. 4 is a front, right, and top perspective view of the cover of the decorative buckle for a light string;
FIG. 5 is a rear, right, and top perspective view thereof;
FIG. 6 is a front view thereof;
FIG. 7 is a rear view thereof;
FIG. 8 is a left side view thereof;
FIG. 9 is a right side view thereof;
FIG. 10 is a top view thereof;
FIG. 11 is a bottom view thereof;
FIG. 12 is a front, right, and top perspective view of the receiver of the decorative buckle attached to an object;
FIG. 13 is a second perspective view of the receiver thereof;
FIG. 14 is a rear, left, and top perspective view of the receiver thereof;
FIG. 15 is a front view thereof;
FIG. 16 is a rear view thereof;
FIG. 17 is left side view thereof;
FIG. 18 is right side view thereof;
FIG. 19 is a top view thereof;
FIG. 20 is bottom view thereof;
FIG. 21 is a front and top perspective view of the cover and receiver of the decorative buckle in a closed position;
FIG. 22 is a rear, right, and top perspective view thereof;
FIG. 23 is a perspective view of the decorative buckle in a closed position, with a lamp string passing through;
FIG. 24 is the perspective view thereof with the top cover removed;
FIG. 25 is a perspective view of a plurality of decorative buckles shown in a position of use; and,
FIG. 26 is another perspective view thereof with a plurality of covers removed.
The broken lines in the drawings illustrate portions of the environment of the decorative buckle for a light string which forms no part of the claimed design.
